UNITED STATES PATENT OFFICE.

ELGIE C. AULD AND GUSTAVE E. HUTTLE, OF SCOTTDALE, PENNSYLVANIA.

METHOD OF AND APPARATUS FOR TRANSPORTING MATERIALS.

Application filed February 3, 1922. Serial No. 533,775.

To all whom it may concern:

Be it known that we, ELGIE C. AULD and GUSTAVE E. HUTTLE, citizens of the United States, and residents of Scottdale, in the 5 county of Westmoreland and State of Pennsylvania, have invented certain new and useful Improvements in Methods of and Apparatus for Transporting Materials, of which the following is a specification.

10 This invention relates to the conveyance of mined materials such as coal or mineral ores within mines, and has for one of its objects the provision of a system using an endless conveyer for carrying the material 15 through the mine to suitable storage or loading bins at or adjacent to the mouth of the mine.

In the existing mines it is the general 20 practice to load the mined material into small mine cars adjacent to the point of mining, and to then push or otherwise convey these cars out to the corridors or headings of the mine. The loaded cars, either singly or in trains, are then hauled by 25 mules or other suitable means through the corridors or headings to tipples or loading bins at the mouth of the mines. Handling the mined materials in this manner requires the use of tracks which are expensive, a large 30 and constantly increasing equipment of cars, and numerous mules or other conveying means for hauling the cars, and also requires the employment of many skilled men for handling the cars, building or extending and 35 keeping the tracks in repair, etc.

Our system utilizes the cars and tracks within the rooms and sub-entries, the material as mined being loaded into the cars in the usual manner. The loaded cars as filled 40 are pushed or otherwise conveyed the short distance necessary to haul them to the main corridor or entry where they are run upon an unloading or dumping device which empties the cars and distributes the mined material upon an endless conveyer of which 45 an operatively connected series of units extend through the main entry to a loading tipple or bin at the mine outlet where the material is discharged from the conveyers.

50 One object of our invention is to provide a practical, cheap and highly efficient conveying system for receiving and handling

mined materials in transporting the materials through and out of the mines.

One application of our system is illustrated in the accompanying drawings, in which—

Figure 1 is a sectional plan showing the tipple or outlet, and Figure 1^a the inner end 55 of a mine equipped with a haulage system embodying our invention. A complete plan 60 will be had by joining Figures 1 and 1^a on the lines x—x.

Figure 2 is a sectional elevation of the 65 part of the mine shown in Figure 1, and Figure 2^a a similar sectional elevation of that portion of the mine shown in Figure 1^a, a complete sectional elevation being shown 70 by joining Figures 2 and 2^a on the lines y—y.

Figure 3 is an enlarged side elevation of 75 a portion of the conveyer system showing the delivery end of one conveyer unit in relative position with respect to the receiving end of the next unit.

Figure 4 is a top plan of the driving 80 mechanism used for each conveyer unit.

Figure 5 is an end elevation of one form 85 of dumping device usable in emptying the loaded tram cars.

Figure 6 is a side elevation of the dumping device of Figure 5.

Figure 7 is a diagrammatic plan of the 85 conveying system of this application as applied to a mine having a plurality of sub- entries.

The particular embodiment of our invention disclosed herein, although capable of use in connection with handling of other materials in places analogous to a mine, is 90 particularly designated with reference to the handling of mined coal within a mine, and, as shown herein, is composed of a plurality of landings within the mine having revolving dumps within ready access to the mining face of the coal seam and a system of conveyers passing under all of the dumps, each conveyer discharging its load upon a 95 succeeding one. Tightening means are provided for keeping the conveyers taut and also other means for causing an even distribution of the coal upon the conveyers.

The invention will now be described in detail, referring to the drawings by reference

characters, the same characters being used to designate like parts throughout the several views.

- In the drawings, the letter A designates 5 the main entry or corridor of a mine having a plurality of sub-entries or rooms B leading therefrom. The rooms B also may be sub-divided when found desirable or necessary.
- 10 The usual tracks 2 are provided in the sub-entries or rooms B, and along the inner end of the main entry on which the usual tram cars 3 are adapted to travel, and the coal being mined is transported in the cars 3 from
- 15 the mining face of the coal to the nearest or most convenient one of the conveyer loading points or landings C.

Our improved endless belt conveyer system starts from this landing or point C, 20 which comprises a rotary dumping device D (to be described in detail later), which unloads the tram cars 3, and delivers the unloaded coal through a distributing chute 6 onto one of the units 7 of the endless 25 conveyer. It will, of course be understood that any desired form of car emptying mechanism may be used in lieu of the rotary dumping mechanism shown.

The dumping device D is supported upon 30 a suitable framework 8 above a pit 9 formed in the entry and comprises a hopper 10, which has its open bottom joined to the distributing chute 6. A rotary cylinder or barrel 11 is mounted in the upper portion 35 of the hopper 10 which is adapted to be rotated on anti-friction rollers 12, either by hand or power. The barrel 11 is adapted to receive the tram cars 3 for dumping, being provided with track rails 14 which 40 normally are in line with the track rails 2 in the entry, and suitable securing or locking plates or flanges 15 are provided, which are secured to and extend out from the sides of the member 11 to engage over the hubs or ends of the axles of the cars to lock 45 the cars in position when the barrel 11 is rotated in removing the coal from a loaded car.

An endless conveyer, which extends from 50 the landing or point C along the main entry and out past the mine entrance to a suitable distributing point, is conveniently formed of a plurality of conveyer units 7, each unit being similar in construction, and each being provided with a suitable automatic 55 tightening means.

The units 7 comprise an endless belt 5 which may be made of any of the various known materials usable in forming endless 60 conveyers.

Each of the conveyer units 7 is trained 65 about idler rollers 16 and 17 at the ends thereof and passes over suitable supporting rollers 18. The roller 16 at the forward end of each unit is in a higher plane than

the other rollers, thereby causing the forward end of the conveyer to extend forwardly and upwardly at an angle to the plane of the greater portion of the length of conveyer.

Suitable driving mechanism and conveyer tightening means, preferably located at the rear of the roller 16 and in a lower plane, comprises power driven rollers 19 and 20 journaled in a stand 21, and receiving power from a motor 22 or other suitable prime mover, through a shaft 23 and the reducing gears 24, 25, 26, 27, and 27^a. The reverse or under side of the conveyer is trained over and under the roller 19, and over and under the roller 20, in this way securing a maximum surface contact on the rollers. A spring tensioned tightening roller 28 is mounted at the rear of the roller 19, and is adapted to bear upon the reverse 80 portion of the conveyer member 7 to take up any slack, thus keeping the conveyer belt taut at all times.

One end of each of the conveyer units 7 overlaps the rear end of a succeeding unit 90 and discharges into a distributing chute 6^a which distributes the conveyed material upon the receiving end of the succeeding conveyer.

While we have only shown one landing C 95 in Figures 1, 1^a, 2 and 2^a, any desired number may be employed, in such case the landings leading from sub-main entries or passages, as shown diagrammatically in Figure 7. Each landing will be provided 100 with a dumping mechanism and pit as before described, it being understood that the conveyer unit 7 which terminates at the landing extends down into the pit and under the hopper and distributing chute 6. 105

It will be apparent that a conveyer system of any length may be built by multiplying the number of units 7, and that the length of each unit will depend upon conditions within the mine, such as the alignment of the heading. The conveyer system may start from any point within the mine and extend to a point outside of the mine and along the surface on the exterior of the mine, to any suitable terminal such as the river terminal loading bins 30, shown in Figures 1 and 2.

In the practice of our improved method the coal or other material being mined, as 115 mined is loaded into the mine cars 3 and the loaded cars are then pushed from the rooms or sub-entries into the main heading and to the landing C. The loaded cars are then transferred to the car unloading mechanism D and emptied into the receiving and distributing chute 6, and the mined materials are delivered by the chute 6 upon the receiving end of the first of the endless conveyer units 7. This endless conveyer 125 unit 7 then transfers the mined materials to 130

a receiving chute 6^a and the materials are discharged and distributed by the chute 6^a upon the receiving end of the next of the conveyer units 7. The mined materials are 5 then carried forwardly to the main entrance to the mine by the conveyer units 7, being successively transferred from one unit to the next, and finally being discharged adjacent to the mouth of the mine into a suitable bin or loading terminal 30.

As the mine becomes deeper, the initial equipment of mine cars and tracks will be moved further into the mine, and from time to time an endless conveyer unit 7 with 10 its discharge hopper and driving mechanism will be added to the equipment, the dumping mechanism being moved also, or else an additional car dumping mechanism being added. By using standardized endless conveyer units, a spare unit can always be kept on hand in readiness to be added to the haulage system.

The many advantages of our improved conveyer system, which will be readily appreciated by those skilled in the art, result 15 from the avoidance of constantly increasing the length of the mine car tracks and adding to the number of mine cars and mine car hauling equipment, as is necessary 20 in existing mine haulage systems, with an increase in the capacity of the mine or increase in the length of haulage of the mined materials.

Instead of making up trains of loaded 25 mine cars and hauling the loaded cars through the mine to its mouth, and, after being emptied, hauling the empty cars back into the mine to the place or places of loading, a comparatively small number of mine cars and limited amount of mine track is all 30 that is necessary, and the mine cars together with the continuously operating endless conveyer units enables a practically constant supply of coal being carried from the mine.

45 By removing the coal in a practically constant stream instead of intermittently as in the old haulage systems using trains of cars, the necessary capacity of the endless conveyers in order to handle the output of the mine is greatly reduced and the cost of 50 maintenance correspondingly lessened.

Many modifications in the construction and arrangement of the apparatus used in 55 practicing our improved method may be made without departing from the invention as defined in the appended claims.

We claim—

1. In a mine the combination with the mine heading, of a car track in said heading, 60 said track having a series of mine cars thereon, a car unloading mechanism within said heading for emptying loaded mine cars hauled thereto on said car track, and an endless conveyer system arranged to receive and 65 transfer to the mine entrance the mined ma-

terials delivered by said car emptying mechanism to said conveyer system.

2. In a mine the combination with the mine heading, of a car track at the inner end thereof, said track having a series of 70 mine cars thereon, a car unloading mechanism within said heading for emptying loaded mine cars hauled thereto on said car track, and an endless conveyer system extending through said heading and adapted 75 to receive and transfer to the mine entrance the mined materials delivered by said car emptying mechanism to said conveyer system.

3. In a mine the combination with the mine heading, of a car track adjacent to the inner end thereof, said track having a series of mine cars thereon, a car unloading mechanism in said heading for emptying loaded mine cars hauled thereto on said car track, 80 an endless conveyer system extending through said heading and adapted to carry to the mine entrance the mined materials delivered to said conveyer system by said car emptying mechanism, and means at the 85 mine entrance arranged to dispose of the mined materials delivered thereto by said endless conveyer system.

4. In a mine the combination with the mine heading, of a car track at the inner end of said heading, said car track having a series of mine cars thereon, a car unloading mechanism in said heading for emptying loaded mine cars hauled thereto on said car track and an endless conveyer system 100 arranged to receive and convey to the mine entrance the mined materials delivered to said conveyer system by said car emptying mechanism, said conveyer system comprising a plurality of separate units and one unit being arranged to deliver materials carried thereby to another unit of said conveyer system.

5. In a mine the combination with the mine heading, of a car track at the inner end of said heading, said car track having a series of mine cars thereon, a car unloading mechanism in said heading for emptying loaded mine cars carried thereto on said car track and an endless conveyer system arranged 110 to receive and carry to the mine entrance the mined materials delivered thereto by said car emptying mechanism, said endless conveyer system comprising a plurality of separate units and the delivery end of 115 one unit being elevated above the receiving end of another unit to discharge the mined materials thereon by gravity.

6. In a mine the combination with a mine heading, of a car track at the inner end of said heading, said car track having a series of mine cars thereon, a car unloading mechanism within said mine for emptying loaded mine cars carried thereto on said car track and an endless conveyer system arranged to 125 130

receive and carry to the mine entrance the mined materials delivered thereto by said car emptying mechanism, said endless conveyer system comprising a plurality of separate units with the delivery end of one unit elevated and overlapping the receiving end of another unit to thereby discharge the mined materials by gravity.

7. In a mine the combination with a mine heading, of a car track at the inner end of said heading, said car track having a series of mine cars thereon, a car unloading mechanism within said heading for emptying loaded mine cars carried thereto on said car track and an endless conveyer system arranged to receive and carry to the mine entrance the mined materials delivered thereto by said car emptying mechanism, said conveyer system comprising a plurality of separate units having the delivery end of each unit elevated above the receiving end of its adjoining unit, and a hopper arranged to distribute upon the receiving unit the materials discharged into the hopper from the elevated end of the delivery unit.

8. In a mine the combination with a mine heading, of a car track at the inner end of said heading, said car track having a series of mine cars thereon, a car unloading mechanism within said mine for emptying loaded mine cars carried thereto on said car track and an endless conveyer system arranged to receive and carry to the mine entrance the mined materials delivered thereto by said car emptying mechanism, said endless conveyer system comprising a plurality of separate and independently operated units with the end of one unit arranged to discharge materials carried thereby upon the receiving end of its adjoining unit.

9. In a mine haulage system the combination with a mine having a main heading or entry and sub-entries leading therefrom, of a car track connecting said sub-entries with the inner end of said main entry, said car track having a series of mine cars thereon, a car unloading mechanism adjacent to the inner end of said main entry adapted to empty loaded mine cars delivered there-

to on said car track, and an endless conveyer system adapted to receive and transfer to the mine entrance the mined materials discharged upon said endless conveyer system by said car emptying mechanism.

10. The method of conveying mined materials within mines, which consists in loading the mined materials in mine cars at the working face of the mine, transferring the loaded cars to an unloading station adjacent to the inner end of the mine heading, emptying the loaded cars and thereby transferring the mined materials to an endless conveyer system within the mine heading, and carrying the mined materials on the endless conveyer system to the entrance to the mine.

11. The method of conveying mined materials within mines, which consists in loading the mined materials in mine cars at the working face of the mine, transferring the loaded cars to an unloading station adjacent to the inner end of the mine heading, emptying the loaded cars and thereby transferring the mined materials to the innermost unit of an endless conveyer system within the heading, and carrying the mined materials as loaded in said conveyer unit toward the mine entrance and transferring the mined materials from one conveyer unit to the next by gravity in transferring the mined materials to the mine entrance.

12. The method of conveying mined materials within mines, which consists in loading the mined materials in mine cars at the working face of the mine, transferring the loaded cars to an unloading station adjacent to the inner end of the mine heading, emptying the loaded cars and thereby transferring the mined materials to an endless conveyer system within the heading, carrying the mined materials on the endless conveyer system to the entrance to the mine, and discharging the mined materials carried by said endless conveyer system into a receiving hopper adjacent to the mine entrance.

In testimony whereof, we have hereunto set our hands.

ELGIE C. AULD.
GUSTAVE E. HUTTLE.
